INITIAL HOLDER OR SIMILAR ARTICLE

Abraham D. Bobrow, New York, N. Y.

Application August 11, 1954, Serial No. 31,813

Term of patent 3½ years

(Cl. D14—6)

Fig. 1

I claim:

The ornamental design for an initial holder or similar article, as shown.
